UNITED STATES PATENT OFFICE.

JOHN B. BRADY, OF SOMERSET, MARYLAND, ASSSIGNOR TO MORKRUM COMPANY, OF CHICAGO, ILLINOIS, A CORPORATION OF MAINE.

RADIO TELEGRAPH SYSTEM.

Application filed February 24, 1925. Serial No. 11,268.

To all whom it may concern:

Be it known that I, JOHN B. BRADY, a citizen of the United States, residing at Somerset, in the county of Montgomery and State of Maryland, have invented certain new and useful Improvements in Radio Telegraph Systems, of which the following is a specification.

This application is a continuation in part 10 of my application Serial No. 657,061, filed August 13, 1923, allowed April 14, 1924.

My invention relates broadly to radio communication, and more particularly to radio telegraph systems employing automatic 15 means for transmitting signals and automatically recording the signals in print at the receiving station.

One of the objects of my invention is to provide means for automatically controlling 20 the speed of automatic transmitting apparatus and correspondingly controlling the speed of automatic printing receiving apparatus at a distant radio receiver.

Another object of my invention is to 25 provide means for maintaining constant speed of both an automatic radio transmitting apparatus and an automatic printing receiving apparatus so arranged that no interference is offered to the operation of electron tube circuits employed in high amplification radio receiving apparatus and relay apparatus associated with the receiving printer or with the electron tube modulator or oscillator circuits at the transmitter.

30 A still further object of the invention is to provide an electronic control circuit for governing the speed of automatic printer transmitting apparatus and automatic printer receiving apparatus situated at distances one from the other.

Other and further objects of my invention will be understood from the following specification by reference to the accompanying drawings, in which:

Figure 1 represents a radio transmitting installation with an automatic transmitting apparatus under control of an electron tube circuit; Fig. 2 shows a radio receiving circuit having an automatic printer apparatus 45 connected therein and under control of an electron tube circuit; Fig. 3 is a diagrammatic view of a portion of the frame of the rotative mechanism of the automatic apparatus at both the radio transmitter and receiver showing the arrangement of the elec-

tron tube control circuit with reference to the driving motor on the apparatus; Fig. 4 is a side elevation of the driving motor and centrifugal governor showing the slip rings and brush connections by which electrical 60 connections are completed with the electron tube control circuit; and Fig. 5 is a front elevation of the governor illustrated in Fig. 4.

My invention employs automatic apparatus known as the teletype, manufactured by the Morkrum Company of Chicago, Illinois, the invention of Charles L. and Howard L. Krum, in combination with radio transmitting and receiving apparatus. The 65 details of construction of this equipment are set forth in an application for patent filed by Charles L. and Howard L. Krum, Serial No. 477,012, filed June 15, 1921, and Serial No. 673,273, filed November 7, 1923, 70 and also in John B. Brady's Patent No. 1,485,212, dated February 26, 1924.

Heretofore, various mechanical devices have been used for controlling the speed of 75 the individual units of apparatus which have in general included a make-and-break contact device producing a spark discharge across the contacts thereof, which spark discharge occurring in an associated circuit forms in itself a minute radio transmission 80 system interfering with the functioning of the electron tube circuits associated with the automatic apparatus and with other radio circuits in the vicinity. In speed controlling 85 means heretofore employed in an automatic printer radio receiving installation, the spark discharge sets up a continuous disturbance in the electron tube amplification and relay circuits through which the operating 90 impulses for the teletype printer must be received.

This interference has been particularly objectionable where the automatic printer receiving apparatus has been employed at a central radio receiving center 95 where a great many channels of radio reception are being operated simultaneously on separated frequencies some actuating photographic recording apparatus, some connected to ink tape recorders and still others connected to a local telephone circuit where the signals are translated mentally by an operator and copied down by hand or on the typewriter. In such installations as these it

100 has been found that the sparking at the governor has a tendency to reduce the efficiency 105 110

of the other means of recording and actually interferes therewith. This spark discharge and resulting electrical disturbance is particularly objectionable in radio printer systems as it often tends to actually annul the printer signals and render the system inoperative. By my present invention I eliminate this undesirable interference in the electron tube circuits.

10 I have illustrated the invention at the transmitting station in connection with a direct automatic keyboard control, but it will be understood that automatic tape impulse transmission may be used and the speed of the apparatus maintained at a predetermined constant value by the electronic control circuit to be hereinunder described.

Referring to Figure 1 of the drawings reference character 1 indicates a radio transmitting antenna system having ground connection 2. The radio transmitting apparatus has been represented diagrammatically at 4. A source of sustained oscillations is provided which may be an electron tube generator as shown, an alternator, an arc generator or other source of continuous wave energy. I have illustrated by way of example, electron tube oscillators 5, 6 and 7 having their grid, filament and plate electrodes connected in parallel and the grid and plate circuits interlinked through antenna inductance 8. It will be clear that a single tube oscillator may be used and the other tubes arranged to increase the amplitude of the oscillations. The signaling impulses may be produced by changing the condition of the oscillator circuit by means of relay 9. The control coils 10 of this relay are connected through a local battery 11 with the contacts 12 and 14 of the transmitter 15. The driving motor 16, through the medium of a distributing cam shaft or the like, operates the transmitter contacts 12 and 14 and causes radiation or suppression of impulses of energy from the antenna system 1 through a definite number of successive timed impulses for each character signal. The speed of the motor which thus determines the timing of the transmitted impulses during each signal period, is uniformly maintained at the desired rate by means of the electron tube circuit 18. In the arrangement shown, motor 16 is a series wound, direct current machine and its armature 19 is supplied with current from a source 20, which also supplies the series field coils 21. The motor 16 is provided with a centrifugal type of governor as shown in Figs. 4 and 5 housed within the chamber 22, forming a fly wheel for the motor. A movable arm member 23 is provided within the fly wheel housing 22 mounted on spring strip 24, mounted on post 25 within the fly wheel housing. The arm member is arranged to be actuated by centrifugal force against the

action of coil spring 26, the tension in which is adjustable by screw 27.

The arm member 23 is shown arranged to make successive connection with a contact 28 or a contact 29 located opposite contact 28. The arm 23 is connected with the filament circuit 34 of electron tubes 30 and 31. A divided grid circuit 35 is provided, one path being completed through negative battery 32 to contact 28 toward which arm 23 is pressed by its spring and the other circuit being completed by arm 23 moving to the other contact 29 under centrifugal action. The contact 29 contacts to positive battery 40. The relatively large negative charge from battery 32 on the grids of the tubes 30 and 31 has the tendency of preventing any current flow in the plate circuit 36. The plate circuit contains high potential battery 37 and auxiliary field coils 38 wound in the same direction as the main field coils 21 in such manner that when current flows through the auxiliary field winding 38 the flux through the field coils 21 is increased. The arm 23 moves off of contact 28 immediately upon any increase in speed of motor 16 in accordance with centrifugal action. The arm then connects with contact 29 placing a positive charge on the grids of tubes 30 and 31 of battery 40. A current now commences to pass in the plate circuit 36 and inasmuch as the flow of current through the auxiliary field winding 38 is in the same direction as that through the main field winding 21, the flux in the field increases causing the motor speed to be reduced, whereupon arm 23 returns to contact 28 returning negative polarity to the grids and stopping further passage of current in the plate circuit 36.

At the distant receiving station an antenna system 41 may be employed having radio receiving apparatus coupled therewith. I have shown by way of example two stages of radio frequency amplification obtained by means of electron tubes 42 and 43, a detector 44 which may be coupled with a local oscillator for heterodyne reception, and tubes 45 and 46 serving as an audio frequency amplifier of the received impulses. The impulses operate a power tube relay 47 having an input circuit selectively tuned to the tone frequency of the incoming impulses. The output circuit of the power tube relay 47 includes the windings of a sharply responsive mechanical relay 48 which closes a local circuit 49 through teletype magnet coils 50. The magnet coils 50 attract an armature which operates to control the automatic printing of characters represented by the particular impulses radiated from the distant transmitter on operation of contacts 12 and 14.

The automatic printing apparatus is operated and timed in operation during each

signal period by a motor 16' similar to that at the distant transmitter which effects and times the operation of the transmitter contacts. Preferably, the motor operates the 5 rotary distributing member of the printing apparatus through the medium of the clutch which, in response to received impulses, is tripped into operation at the beginning of each signal period. In such cases, it is de- 10 sirable that the receiving distributor rotates slightly faster than the transmitting distributor and this is preferably effected by interposing suitable gearing between the motors and parts operated thereby, so that 15 both motors may be set for operation at the same speed. An electron tube control circuit 18' is arranged at the receiver and adjusted and set with respect to the electron tube control circuit 18 at the transmitter. 20 Tubes 30' and 31' having characteristics similar to the characteristics of tubes 30 and 31 are employed. The grid circuit 35' is divided as at the transmitter and contains a corresponding source of negative potential 32' nor- 25 mally connected with the grid circuit through contact 28' whereby no current flows in the plate circuit 36'. Should motor 16' tend to run faster than motor 16 or increase above normal speed, arm 23 moves to contact 29' 30 placing a positive charge from battery 40' on the grids of the tubes 30' and 31' thereby causing a passage of current in the plate circuit 31' through auxiliary coils 38' increasing the field of coils 21' and bringing 35 the motor 16' back to predetermined speed with the motor 16 at the distant transmitter.

Figure 3 of the drawings shows on enlarged scale the electron tube control circuit for the motor 16 wherein the motor is ill- 40 lustrated as driven from a source 61 with auxiliary coil 38 coupled with the field winding 21.

In Figures 4 and 5 the cylindrical housing 22 for the centrifugal governor is ill- 45 lustrated as having three slip rings 52, 53 and 54 which are connected interiorly of the cylindrical housing 22 with the terminals 25, 28 and 29 and to which sliding connection is made from the exterior of the motor 50 through brushes 57, 58 and 59. The brushes are carried on insulated block 56 and contact with the slip rings 52, 53 and 54. Connections such as the leads 60, represented in Fig. 5, are taken from the terminal block 56 to the electron tube circuits as clearly set forth in Fig. 3. The usual speed control spots 55 are provided on the exterior of the 55 governor housing 22 for initially setting the speed of the machine.

Both the transmitting and receiving ma- 60 chines are initially adjusted through processes of factory inspection to operate at a predetermined speed and the electron tube circuits are arranged to maintain the ma- 65 chines at this selected speed without the the receiver, a printer operated thereby,

production of sparking which has been heretofore a continuous source of interference in the operation of radio printer systems.

The operation of this system has been described in conjunction with the preceding 70 description. It will be clear that this automatic printing apparatus may be used side by side with manual receiving apparatus without interference in the telephone receivers of the latter type of system by the automatic printing apparatus. It will also be understood that a construction of electron tube may be employed which controls a relatively large plate current and thereby permit speed control apparatus at both the 80 transmitting and receiving station to be small and compact.

While I have described my invention in a particular embodiment, it will be understood that modifications may be made and 85 that I intend no limitations upon the invention other than those imposed by the scope of the appended claims.

What I claim and desire to secure by Letters Patent of the United States is as fol- 90 lows:

1. A system of radio communication comprising in combination a radio transmitter, means for automatically transmitting signals in groups of impulses of energy, a radio 95 receiver, electrical means for receiving said impulses of energy, mechanical means for automatically receiving said impulses and causing characters represented by partic- 100 ular groups of impulses to be simultaneously printed and electron tube circuits at both said transmitter and receiver for maintaining said automatic transmitting means and said automatic receiving means within a predetermined range of speed. 105

2. A system of radio communication comprising in combination means for transmitting radio frequency energy in groups of impulses of energy, an electron tube circuit for maintaining the radiation of said im- 110 pulses of energy at predetermined speed, a receiving apparatus having means automatically responding to said impulses of energy for printing a character represented by each particular group of impulses and 115 an electron tube circuit for maintaining said means at substantially the same speed as said transmitting means.

3. A system of radio communication comprising in combination a transmitting apparatus, a source of oscillations, rotating mechanism for causing radiation of said os- 120 cillations in groups of impulses of energy, an electron tube circuit, for maintaining said rotating mechanism at predetermined speed whereby the speed of transmission of said impulses is predetermined, a receiving apparatus for automatically receiving said impulses of energy, rotating mechanism at 125 the receiver, a printer operated thereby, 130

and an electron tube circuit for maintaining said rotating mechanism at a speed definitely related to the speed of said rotating mechanism at said transmitter whereby a 6 character represented by a particular group of said impulses is simultaneously printed.

4. A system of radio communication comprising in combination a transmitting apparatus, a source of oscillations, rotating 10 mechanism for causing radiation of said oscillations in groups of impulses of energy, a receiving apparatus for automatically receiving said impulses of energy, rotating mechanism at the receiver, a printer operated thereby, a driving motor at both said transmitter and receiver arranged to drive said rotating mechanism, a field winding for said motor, an electron tube apparatus having grid, filament and plate circuits, 15 means actuated by said motor for selecting the potential of said grid circuit, means connected in said plate circuit and related to said field winding to control the effective field of force whereby said apparatus at said 20 transmitter and receiver operates at predetermined speed for the automatic transmission and reception of signals in print.

5. A system of radio communication comprising in combination a transmitting apparatus, a source of oscillations, rotating 30 mechanism for causing radiation of said oscillations in groups of impulses, a receiving apparatus for automatically receiving said impulses of energy, rotating mechanism at the receiver, a printer operated thereby, a driving motor at both said transmitter and receiver arranged to drive said rotating mechanism, a field winding for said motor, an electron tube apparatus having grid, filament and plate circuits, means actuated by 35 said motor for normally charging said grid circuit negatively, a coil winding connected in said plate circuit and magnetically coupled to said field winding, means actuated by said motor under conditions of increase in speed for charging said grid circuit positively whereby said coil winding normally is electrically inert but operates to increase the magnetic flux emanating 40 from said field winding when said grid circuit is charged, positively operating the apparatus of said transmitter and receiver at predetermined speed for the automatic transmission and reception of signals in print.

6. A system of radio communication comprising in combination a transmitting apparatus, a source of oscillations, rotating mechanism for causing radiation of said oscillations in groups of impulses of energy, a receiving apparatus for automatically receiving said impulses of energy, rotating mechanism at the receiver, a printer operated thereby, a motor at both said transmitter and receiver arranged to drive said rotating

mechanism, a field winding for said motor, an electron tube apparatus having grid, filament and plate circuits, means actuated by said motor under conditions of varying speed for varying the polarization of said 70 grid circuit, a coil winding series connected in said plate circuit and coupled to said field winding whereby said field winding has its field of force increased under conditions of increase in motor speed causing said 75 motors to operate within predetermined speed at said transmitter and receiver for the automatic transmission and reception of signals in print.

7. A system of radio communication comprising in combination a transmitting apparatus, a source of oscillations, rotating mechanism for causing radiation of said oscillations in groups of impulses of energy, a receiving apparatus for automatically receiving said impulses of energy, rotating mechanism at the receiver, a printer operated thereby, a motor at both said transmitter and receiver arranged to drive said 80 rotating mechanism, a field winding for said motor, an electron tube apparatus having grid, filament and plate circuits, centrifugal means actuated by said motor under conditions of varying speed, a pivotal arm operated by said centrifugal means, and 85 electrical means controlled by said arm for varying the polarization of said grid circuit, a coil winding series connected in said plate circuit and coupled to said field winding whereby said field has its field of force 90 increased under conditions of increase in motor speed causing said motors to operate at predetermined speed at said transmitter and receiver for the automatic transmission and reception of signals in print.

8. A system of radio communication comprising in combination means for automatically transmitting radio frequency energy in groups of impulses of energy, an electron tube circuit for maintaining the radiation 100 of said impulses of energy at predetermined speed, a receiving apparatus having means automatically responding to said impulses of energy for printing a character represented by each particular group of impulses, 110 rotary mechanism for driving said automatic means at both said transmitter and receiver, centrifugal means connected with said rotary mechanism, a pair of contacts, a switch arm arranged to contact with one of 115 said contacts when said rotary mechanism is operated at required speed and make connection with said other contact when said centrifugal means is actuated, an electron tube apparatus having an input and output 120 circuit, sources of energy of opposite polarity connected with said contacts and a circuit arrangement whereby said switch arm in making and breaking said contacts varies 125 the polarity of said input circuit and means 130

- in said output circuit for correspondingly controlling the speed of said rotary mechanism at said transmitter and receiver.
9. A system of radio communication comprising in combination means for automatically transmitting radio frequency energy in groups of impulses of energy, an electron tube circuit for maintaining the radiation of said impulses of energy at predetermined speed, a receiving apparatus having means automatically responding to said impulses of energy for printing a character represented by each particular group of impulses, rotating mechanism for driving said automatic means at both said transmitter and receiver, a centrifugal means connected with said rotary mechanism, a switch arm carried by said centrifugal means, a pair of independent contacts arranged to be separately closed by said switch arm, a local source of positive polarity connected with one of said contacts, and a local source of negative polarity connected with the other of said contacts, an electron tube apparatus having grid, filament and plate circuits, connections between said grid circuit and each of said local sources, and a connection between said filament and said switch arm whereby variation in speed causes variation in polarity of said grid circuit, and means in said plate circuit for controlling the speed of said rotary mechanism at said transmitter and receiver.
10. In a radio printing apparatus, the combination with a rotating distributor, of an operating motor therefor, means for maintaining the motor speed at the desired rate comprising an electron tube circuit, and a centrifugal governor driven by the motor for controlling said circuit. 35
11. In a radio printing apparatus, the combination with a rotating distributor, of an operating motor therefor, means for maintaining the motor speed at the desired rate comprising a divided electron tube circuit arranged to function in a plurality of different conditions and a centrifugal governor driven by the motor for controlling said circuit. 40
12. In a radio printing apparatus, the combination with a rotating distributor, of an operating motor therefor, means for maintaining the motor speed at the desired rate comprising an electron tube circuit having a pair of independent input circuits and a centrifugal governor driven by the motor for controlling connections to each of said circuits independently. 55

In testimony whereof I affix my signature.

JOHN B. BRADY.
